FRANK BRADY.

By Attorney

Attorney.

UNITED STATES PATENT OFFICE.

FRANK BRADY, OF DENVER, COLORADO.

HYDROCYCLE.

Application filed August 9, 1921. Serial No. 490,938.

To all whom it may concern:

Be it known that I, FRANK BRADY, a citizen of the United States, residing at the city and county of Denver and State of Colorado, have invented certain new and useful Improvements in Hydrocycles; and I do declare the following to be a full, clear, and exact description of the invention such as will enable others skilled in the art to which it appertains to make and use the same, reference being had to the accompanying drawings and to the characters of reference marked thereon, which form a part of this specification.

This invention relates to manually propelled water craft of the type usually referred to as hydrocycles and has reference more particularly to the operating mechanism by which the operator transmits power to the propelling apparatus.

I am aware that water vehicles have been made which comprise a pair of pontoons which are connected together in parallel relation and equipped with a bicycle or bicycle-like apparatus by which the operator generates power by applying his feet to pedals in the usual way, the power thus generated being transmitted to a propeller of either the screw or paddle wheel type.

It is the object of my invention to improve the type of water vehicle referred to above and to devise an operating mechanism that will be adapted to be operated simultaneously by two people, one of whom operates a pair of pedals and uses his hands for steering while the other operates a lever. The power generated by the pedals and the lever is transmitted, by means of proper mechanism, to a propeller shaft.

One object of my invention is to design a hydrocycle of the type referred to in which the center of gravity is brought closer to the water level than it would be in case the two operators were mounted tandem on elevated seats.

Having thus described my device in a general way I will proceed to describe the same in detail by reference to the accompanying drawings in which—

Fig. 1 is a side elevation of my hydrocycle.

Fig. 2 is a plan view thereof.

Fig. 3 is an elevation or view looking towards the rear.

Fig. 4 is a plan view of the propelling mechanism and

Fig. 5 is a side view of the propelling mechanism.

The same reference characters refer to the same parts throughout the several views.

My improved hydrocycle comprises two pontoons 10 of boat or canoe shape, having decks 11 to which are connected, at spaced intervals, cross bars 12 and 13 which hold the pontoon in spaced parallel relation. Connecting the rear ends of pontoons 10 beneath the water surface is a bar 14 that serves as a bearing for the propeller shaft 15.

Pivotally secured to the rearmost cross bar 12 by suitable means is a rudder 16 which is controlled by the handle bars 17 acting through steering post 18, rods 19 and bar 20, the latter being non-rotatably connected to the rudder post 21.

Secured to one of cross bars 12 and one of cross bars 13 is a frame 22 comprising two bars 23 and 24, to the top of which is secured a suitable bicycle seat or saddle 25.

Secured to bar 13 and one of bars 12 is a frame 26 which carries at its top a bearing 27 in which is journaled a pair of pedals 28 having non-rotatably secured thereto a sprocket wheel 29.

The relationship between the saddle 25 and pedals 28 is such that a person seated on the saddle will be able to operate the pedals with ease. The saddle may, of course, be adjustable in the usual manner so as to accommodate people of different sizes.

Located in front of frame 22 is a seat 30 having a back 31 to which is secured a rearwardly extending portion 32 which forms a bearing for steering post 18, the latter being provided with a collar 33 to hold it in place.

Seat 30 has a forwardly extending portion 34 for the reception and protection of the feet of the occupant. Secured to the foremost ones of members 12 and 13 is a frame 35 to which is pivoted at

36 a lever 37 the purpose of which will hereinafter appear. Lever 37 is provided with two handles 38 which are to be grasped by the hands of the operator.

Referring now more particularly to Figs. 4 and 5, it will be noted that a frame 39 supporting two bearings or pillow blocks

40 and 41 in the former of which is pivotally mounted a shaft 42 carrying a gear wheel 43. Gear wheel 43 has one spoke thereof provided with a pin 44 between 5 which and pin 45 on the end of lever 37 is connected a pitman 46 by means of which the oscillatory motion of lever 37 is caused to rotate wheel 43.

Pivoted in bearing 41 is a shaft 47 to one 10 end of which is secured a sprocket wheel 48, which is in the same plane as sprocket wheel 29, and to the other end is connected a bevel gear 49 and a spur gear 50, the latter meshing with gear 43. A sprocket chain 15 51 serves to transmit power from wheel 29 to wheel 48 and to bevel gear 49. A pinion 52 secured to the end of shaft 15 meshes with bevel gear 49 and transmits the power to propeller 53.

20 The operation of my device is as follows: One of the operators is seated on saddle 25 with his hands grasping handle bars 17 and his feet on pedals 28. The other operator is seated in seat 30 with his feet resting on 25 the floor and his hands grasping handles 38. When the former operator rotates wheel 29 through pedals 28 he transmits motion to wheels 48, 49, 50 and 43 through chain 51. When the operator that occupies seat 30 30 moves lever 37 about its pivot 36 he transmits motion and power to wheels 43, 50 and 49 through pitman 46. It is thus apparent that the power exerted by both operators will be transmitted to bevel gear 49 and from there through pinion 52 and shaft 15 to propeller 53 which will thus be acted upon by the combined power of both operators.

40 Since the pedals 28 can be rotated at a greater speed than the lever 37, I have provided the gears with such relationship that this is accomplished. The lever 37 should preferably make one-half a cycle to each complete revolution of the pedals 28 although the exact ratio is not material and can be varied so as to suit the convenience of the operator by merely changing the sprocket wheel 48 to the size desired.

45 From the above it will be seen that I have provided a motion transmitting means suitable for use on hydrocycles of the pontoon type, or any other type, that is simple in construction and adapted to be operated by two people one of whom is seated on an elevated seat and uses his feet to operate a pair of pedals and the other of whom is comfortably seated nearer the water surface and uses his hands to move a lever. By the means outlined a comparatively great 50 amount of power can be produced and trans-

mitted to the propeller of the vehicle and great speed can thus be attained with a minimum amount of exertion.

Although I have shown my mechanism applied to a pontoon type boat structure 65 it is evident that it can be applied to any type of floating structure as well as to land vehicles of various types.

I desire the foregoing description to be 70 taken in an illustrative sense only and not in a limiting one and I reserve the right to apply my device to any use to which it may be adapted as well as to make such changes therein as may fall within the scope of the 75 appended claim.

I desire to point out that this hydrocycle is made detachable in order that it may be readily disassembled for shipping and for transporting from place to place. When it is desired to ship or transport the device the 80 bars 12 and 13 together with cross bar 14 are detached from the pontoons and the mechanism may also be detached from these bars and the whole packed in a comparatively small box.

If it should be desirable to operate the hydrocycle by one man only the pinion 50 may be moved outwardly on shaft 47 until it becomes disengaged from gear wheel 43, as indicated by dotted lines in Fig. 4. The 85 operator may then be seated on saddle 25 and operate the pedals 28 without turning wheel 43 or operating the lever 37.

Having described my improved device 90 and the best manner in which I contemplate constructing, making and using the same, what I claim as my invention or discovery is:

A mechanical movement comprising a 100 driven shaft provided with a bevel pinion, means for driving said shaft comprising a bevel gear cooperating with said pinion, a gear shaft secured to said bevel gear, a bearing in which said shaft rotates, a sprocket wheel secured to said shaft, a pair 105 of pedals rotatably mounted on an axis substantially parallel to said gear shaft, a sprocket wheel non-rotatably connected to said pedals, a sprocket chain connected to said sprocket wheels, a gear pinion connected 110 to said gear shaft and longitudinally movable thereon, a gear wheel operatively connected with said pinion, a crank pin secured to said gear wheel, a lever pivotally mounted 115 between its ends and a pitman between one end of said lever and the crank pin on said gear.

In testimony whereof I affix my signature.

FRANK BRADY
